By

Robert W. Faustle,

Attorney.

Inventor:

James A. King

UNITED STATES PATENT OFFICE.

JAMES A. KING, OF NEAR NEW PARIS, OHIO.

CASKET SEAL.

Application filed October 11, 1922. Serial No. 598,704.

To all whom it may concern:

Be it known that I, JAMES A. KING, a citizen of the United States, residing near New Paris, in the county of Preble, State of Ohio, have invented certain new and useful Improvements in Casket Seals, of which the following is a full, clear, and comprehensive specification and exposition, the same being such as will enable others to make and apply

10 the same with absolute exactitude.

It has become known that in most instances after burial caskets are buried in the ground that the moisture or water leaks into them so that the corpse contained in the casket is covered with water. In view of this eventuality the primal object of this invention is to hermetically seal the casket in such manner as to absolutely exclude water and moisture therefrom and therefore keep the 20 corpse dry regardless of the conditions outside.

In order to accomplish the above it is necessary to first have a casket and a lid therefor which is impervious to moisture, as my invention contemplates only the sealing of the lid upon the body of the casket, therefore it seems practical to only employ my invention in connection with metal caskets, although it is not to be limited thereto.

30 One manner of carrying out the principles of my invention in a practical manner is shown in the accompanying drawings, in which—

Figure 1 is a perspective view of a casket 35 in which my invention is incorporated, showing the lid open or turned back. Figure 2 is a cross-section of the upper edge portion of the body of the casket, as taken at any point through its extent. Figure 3 is a cross 40 section of the lower edge portion of the lid of the casket, as taken at any point throughout its extent. Figure 4 is a cross section as taken through the upper edge portion of the body of the casket and through the lower 45 edge portion of the lid of the casket, showing the sealing means in operative position, and showing the parts clamped together by the securing means. Figure 5 is a top plan view showing the parts as they would appear with the lid sealed down in operative 50 position. Figure 6 shows a portion of sealing means alone. And Figure 7 shows a cross section of the sealing means alone.

Similar indices denote like parts throughout the several views.

In order that the construction, the operation, and the advantages of my invention may be more fully understood and appreciated, I will now take up a detailed description thereof, in which I will set forth the construction and the operation as fully and as clearly as I may.

As shown in the drawings letter A denotes the body of a casket, which has the outwardly extending horizontal upper edge or 65 face portion B, from the outer edge of which extends the curved molding portion C. The part B forms a flat face of considerable extent, comparatively, and the said parts A, B and C are preferably integral with each other, and they may be of any desired design, and they all extend entirely around the extent of the casket as shown.

Formed in the face of the horizontal portion B, and extending entirely around the body of the casket, is a curved channel D. Letter E denotes the casket lid, which has an outer vertical rim portion F extending therearound. Extending out at right-angles 70 from the lower edge of the portion F is the face portion G, which is adapted to contact flat with the face portion B of the body. Letter H denotes the mold portion of the lid, the same extends upward and inward 75 from the outer edge of the face portion G to the part F, forming a finish of any desired design. The central portion of the mold H is formed flat, that is parallel with the face G, and it is denoted by the letter I. 80

At frequent distances apart apertures J are formed through the part I, each to receive therein one of the thumb screws K. Each of the screw apertures J is immediately above a corresponding screw aperture L 85 formed through the part G, as shown in Fig. 3.

A nut M is adapted to receive the threaded lower portion of its respective screw K, said nuts being secured to the underside of the 100 part B, as indicated in Fig. 4.

A channel N is formed in the face of the portion G, and it corresponds in size and registers with the channel D, but it is oppositely disposed with relation thereto.

Letter P denotes the sealing element,

which preferably is of rubber or the like, the same being round in cross section, and it is of such length as to extend around in the channels D or N it being preferably formed 5 endless in extent.

In practice the casket may be covered or finished to appear as an ordinary wood or other kind of casket, the screws K and the sealing element P being omitted until required. Just prior to placing the casket in its grave the faces of the parts B and G are uncovered. The sealing element P is then laid in the channel D. Next the lid is placed in position whereby the channels 10 N and D will be directly opposite to each other, which will cause the sealing element to also enter the channel N. Now the screws K should be inserted through the apertures J and L, their lower ends entering their respective nuts M. And as the screws K are tightened down to their limits it is apparent that the element P will be clamped in the channels D and N, as shown in Fig. 4, thereby absolutely sealing the joint between the 15 lid and the body of the casket and thereby accomplishing the desideratum of my invention.

I desire that it be understood that various changes may be made in the several details 20 of construction without departing from the spirit of my invention and without sacrificing any of the advantages thereof.

Having now fully shown and described my invention, what I claim and desire to secure by Letters Patent of the United States, is:

In combination with a sheet metal burial casket comprising a body, a horizontal face portion extending outward horizontally from around the upper edge of said body, 40 a molding extending from the outer edge of said face portion to the body and united therewith at a point below said face portion, a lid for said body, a face portion extending out horizontally from the lower edge of said lid and adapted to contact flat with the face portion of the body, a molding extending from the outer edge of the face portion of the lid and secured to the lid at a point above 45 said face portion of the lid, there being 50 channels formed in each of said face portions which channels register with each other and extend entirely around the casket, an endless rubber band which is round in cross section resting in both of said channels and being of such diameter in cross section as to normally space said faces from each other, and a plurality of thumb-screws by which said face portions may be clamped 55 toward each other to compress said rubber band, all substantially as shown and described.

JAMES A. KING.
